BOTTLE SUPPORT

Orie I. Sinclair, Wilmington, Calif.

Application November 25, 1947, Serial No. 788,030

3 Claims. (Cl. 248—312)

1

This invention relates to improvements in bottle hangers or supports and more particularly to an improved device for supporting a bottle, such as a drainage bottle, on a bed or bed-side stand.

Various medical treatments require drainage facilities and some require the use of such facilities over extended periods of time. In the treatment of bladder ailments, for example, it is customary to irrigate and drain the bladder, using a flexible tube and a standard 1000 cc. drainage bottle. At the present time the drainage bottle is secured to the bed, or to a stand adjacent the bed, by a strip of bandage material, adhesive tape or similar material, and the end of the tube at the bottle is similarly tied in place. Under such conditions the removal of the bottle for emptying or cleaning and replacement of the bottle is a difficult and time-consuming operation that frequently involves accidental spilling of the contents of the bottle.

It is among the objects of the present invention to provide an improved bottle-supporting device that is small in size and of light weight, and may be quickly and easily secured to a bottle for ready removal therefrom when desired, which may be hung from the structure of the bed or stand and quickly attached and removed without any danger of accidentally spilling the contents of the bottle, which provides a suitable clip for securing the drainage tube in proper position relative to the bottle, and which can be economically manufactured of inexpensive material.

Other objects and advantages will become apparent from a consideration of the following description in conjunction with the accompanying drawing, wherein:

Figure 1 is a cross-sectional view of a fragmentary portion of a bed showing in side elevation a bottle support illustrative of the invention applied thereto;

Figure 2 is a plan view of a strip of material which provides the band surrounding the bottle neck, as illustrated in Figure 1;

Figure 3 is a vertical cross-section of the improved bottle support on a somewhat enlarged scale; and,

Figure 4 is a top plan view of the bottle support illustrated in Figures 1 and 3.

With continued reference to the drawing, the numeral 10 designates a suitable bottle which may be a standard 1000 cc. bottle such as conventionally used in hospitals for drainage purposes and the numeral 11 designates a flexible rubber drainage tube which leads from the

2

patient supported on the bed into the top of the bottle 10. The bottle is provided with a neck having at its upper or outer end an external annular bead 12, as is conventional.

The fragmentary portion of the bed, as illustrated in Figure 1, includes a mattress 13 supported upon a mattress-spring 14 which is in turn supported upon side boards, one of which is generally indicated at 15 and which may include an upper tubular bar 16 and a lower tubular bar 17. The bed is illustrated principally to indicate the manner of supporting the bottle hanger from a side bar of the bed, but it is to be understood that the hanger may be operatively attached to a bedside stand or other convenient article of furniture as well as to the bed.

The hanger itself comprises, in general, a bottle neck-encircling band 18, a wire bracket 19, a screw 20, and a wing nut 21 for the screw.

The band 18 may be conveniently formed from an elongated strip of thin flexible material, such as thin sheet metal, having parallel-arcuate longitudinal edges and substantially semi-circular ends and apertures 22 disposed one adjacent each end of the strip medially of the width thereof. While the strip constituting the band 18 may be formed of any suitable material, a material such as stainless steel is preferred because of its non-corrosive properties.

When the strip illustrated in Figure 2 is bent to annular form about the neck of a bottle it has a frustro-conical shape, as illustrated in Figure 1, and the smaller end engages the bead 12 at the outer end of the bottle neck to firmly secure the bottle in the band. The rounded end portions are bent outwardly, substantially at right angles to the remainder of the strip to provide a pair of apertured ears 23 to which the bracket 19 is attached by the screw 20.

Bracket 19 is preferably formed of a length of wire of suitable stiffness and preferably of a non-corrosive material, such as stainless steel. This bracket has a substantially straight shank portion 24 at one end of which is provided an integral curved hook 25 having a rounded loop 26 at the outer end thereof and at the opposite end of the shank is provided a substantially circular-apertured lug 27 which is insertible between the apertured ears 23 of band 18 and receives the screw 20, as is clearly illustrated in Figure 3.

A substantially straight stem 28 extends from lug 27 along the shank 24 part way of the length of the shank and has its outer ends turned outwardly substantially at right angles thereto and provided with a curved hook 29 smaller than hook

25 which provides a clip for securing tube 11 in operative position relative to bottle 10, as is clearly illustrated in Figure 1. The outer end of clip 29 is also preferably provided with a substantially circular loop 30 of small diameter to eliminate any sharp points or edges at the ends of the clip. 5

In the arrangement illustrated, shank 24 and stem 28 diverge away from lug 20 at a small angle relative to each other but this angle may be varied as desired to bring the tube clip 29 in proper operative position above the small open end of band 18. 10

Screw 20 is inserted through the apertures in ears 23 and through the apertures in lug 27 which lug is disposed between the ears, and wing nut 21 is threaded down on the screw to clamp the lug 15 between the ears and simultaneously clamp the band 18 about the neck of the bottle to firmly secure the bottle neck in the band. 20

The entire device is simple in construction, requiring only four different parts, is highly effective and efficient in use, as is clearly apparent from an inspection of Figure 1, is convenient to use and supports the bottle from the bed or stand structure in a manner such that the bottle can be quickly and easily emptied without danger of spilling the contents thereof and may be replaced when necessary or desirable. 25

The invention may be embodied in other specific forms without departing from the spirit or essential characteristics thereof. The present embodiment is, therefore, to be considered in all respects as illustrative and not restrictive; the scope of the invention being indicated by the appended claims rather than by the foregoing description; and all changes which come within the meaning and range of equivalency of the claims are, therefore, intended to be embraced therein. 30

What is claimed is:

1. A bottle support comprising a split annular band adapted to surround and engage the neck of a bottle and having an apertured ear at each end. 35

thereof, a wire bracket having a curved hook at one end, an apertured lug at the opposite end, a shank portion extending between said hook and said lug, a stem extending from said lug along said shank and having an end portion directed away from said shank, a curved tube clip provided by said stem end portion, and a fastening element inserted through the apertures in said ears and said lugs to secure said band to said bracket and simultaneously secure said band to the neck of a bottle received therein. 20

2. A bottle support comprising an annular band of thin flexible material adapted to surround a bottle neck and having apertured end portions, and a bracket having an apertured lug insertible between the apertured end portions of said band, a hook on said bracket adapted to engage the structure of a bed or stand, a tube clip on said bracket between said lug and said hook and positioned to overlie said band, and a screw fastener inserted through the apertured end portions of said band and said apertured lug to operatively connect said band to said bracket. 25

3. A bottle support comprising an annular band of frusto-conical shape adapted to surround a bottle neck with its smaller end engaging the bead at the outer end of such bottle neck, said band comprising a strip of thin, flexible material having outwardly directed, apertured end portions providing apertured ears for attaching said band to a bracket; a wire bracket having a shank portion, a curved hook at one end of said shank portion, an apertured lug at the opposite end of said shank portion and insertible between said ears, a stem extending from said lug along said shank portion, and a tube clip on the end of said stem remote from said lug; a screw extending through said apertured ears and said lugs; and a nut on said screw to clamp said ears against said lugs and simultaneously clamp said band about a bottle neck received therein. 40
